DESIGN FOR AN ALPHABET FOR FORMING MONOGRAMS FOR WEARING APPAREL OR SIMILAR ARTICLE

Charles Emmey, New York, N. Y.

Application July 9, 1936, Serial No. 63,752

Term of patent 14 years

To all whom it may concern:

Be it known that I, Charles Emmey, a citizen of the United States, residing in the city and county of New York, State of New York, have invented a new, original, and ornamental Design for an Alphabet for Forming Monograms for Wearing Apparel or Similar Article, of which the following is a specification, reference being had to the accompanying drawing forming part thereof.

The drawing is a plan view of an alphabet for forming monograms for wearing apparel or similar article showing my design. The face of each of the letters of the alphabet, as shown, is characterized by V-shaped stitchings. The letters forming the alphabet as shown are of no appreciable thickness.

I claim:

The ornamental design for an alphabet for forming monograms for wearing apparel or similar article substantially as shown and described.

CHARLES EMMEY.
